PAPERBOARD BASKET STRUCTURE FOR FRUIT
AND THE LIKE

Clifford H. Keith, Miami, Fla., assignor, by mesne assignments, to The Mead Corporation, Dayton, Ohio, a corporation of Ohio

Filed Sept. 18, 1957, Ser. No. 684,698

5 Claims. (Cl. 229—16)

This invention relates to baskets of the type employed for packing fruit or other produce and the like, and more particularly to an improved basket structure of this sort that is formed entirely of paperboard and that is collapsibly arranged to allow the basket structure to be blanked and preformed in collapsed position for convenient shipping and storage when empty, while being easily and rapidly set up to erect position when ready for use without requiring any securing operation whatever in the course of erection.

These and other features of the present invention are described in further detail below, in connection with the accompanying drawings, in which:

Fig. 1 is a perspective view of a paperboard basket structure embodying the present invention and shown optionally fitted with a separate liner structure of corresponding form nested therein;

Fig. 2 is a transverse sectional detail taken substantially on the line 2—2 in Fig. 1;

Fig. 3 is a plan view of the form of blank employed for the basket structure illustrated in Figs. 1 and 2;

Fig. 4 is a corresponding plan view showing the basket structure preformed in collapsed position from the blank illustrated in Fig. 3; and

Fig. 5 is a further perspective view illustrating the manner in which the basket structure is erected from the collapsed form illustrated in Fig. 4.

The basket structure of the present invention as illustrated in Figs. 1 and 2 is indicated generally by the reference numeral 10, and the separate optional liner structure by the reference numeral 10'.

The paperboard basket structure 10 comprises, as seen most completely in Fig. 3, a bottom wall panel 12 that is preferably hexagonal in form and that is medially foldable across corners thereof along a score line 14. Alternatively, the bottom wall panel 12 might have any symmetrical polygonal form in which the number of sides total two plus a multiple of four.

At each side edge of the bottom wall 12 a liner panel 16, 18, 20, 22, 24 and 26 is foldably hinged, with the pair of liner panels 16 and 22 at the opposed side edges of bottom wall panel 12 that are parallel with the medial score line 14 therein also being medially foldable at parallel axes along score lines 28 and 30.

At the respective edges of each medially foldable liner panel 16 and 22, opposite the bottom wall panel 12, a foldably hinged series of side wall panels 32, 34, and 36, and 38, 40 and 42 are foldably hinged at the middle panel 34 and 40 of each series. The total number of side wall panels 32 to 40 correspond to the number of liner panels 16 to 26, and the middle side wall panels 34 and 40 are preferably hinged on the medially foldable liner panels 16 and 22 at double score lines 44 and 46 to facilitate erection of the basket structure 10 and strengthen the erected structure as explained further below. In addition, one terminal side wall panel 32 and 38 of each series, at complementary positions in the respective series,

2

have foldable securing flaps 48 and 50 formed thereon; and at least one opposed pair of the liner panels that are not medially foldable, such as 18 and 24, or 20 and 26, and the corresponding side wall panels 32 and 38, and 42 and 36, are advantageously formed with handle means as indicated at 52, 54, 56, 58, 60, 62, 64 and 66.

The paperboard blank for the basket structure 10 as illustrated in Fig. 3 is preferably formed of corrugated paperboard with the corrugations running parallel with the medial folding axis of the bottom wall panel 12, as indicated in Fig. 3, and consequently extending angularly in and thereby additionally stiffening a majority of the liner panels 18, 20, 24 and 26. Also, all of the liner panels 16 to 26 are preferably formed according to the present invention with a taper toward the foldably hinged edges thereof at the bottom wall panel 12, and the respective side wall panels 32 to 42 are formed coextensively, so that the stiffening effect of the angularly extending corrugations is carried into the corresponding side wall panels 32, 36, 38 and 42 as well, and the tapering form of the liner and side wall panels provides a wedged supporting action for the bottom wall panel 12 in the erected basket structure 10 as is also pointed out further below.

Fig. 4 of the drawings illustrates the manner in which the blank of Fig. 4 may be folded and secured to preform the basket structure 10 in collapsed position. For this purpose, the blank of Fig. 3 is folded at the medial bottom wall score line 14 to double the bottom wall panel 12 upon itself and to arrange the respective liner panels 16 to 26 and side wall panels 32 to 42 at opposite sides of the medial bottom wall fold line 14 in face to face relation, whereupon the flap members 48 and 50 on the side wall panels 32 and 38 may be secured by stapling or the like to the respective face to face adjacent side wall panels 36 and 42 and thereby form an endless foldably hinged series including all of the side wall panels 32 to 42. In this collapsed Fig. 4 form, the basket structure 10 may be compactly arranged in a supply stack for shipment to and storage by the ultimate user until ready for use, at which time the ultimate user is required only to fold the collapsed basket structure 10 to erect position for use without having to secure the structure in any way to maintain it erect.

The manner in which the collapsed Fig. 4 form of the basket structure 10 may be set up to erect position is illustrated in Fig. 5 as consisting simply of opening the endless series of side wall panels 22 to 42 and inserting the medially folded bottom wall panel 12 therein with the liner panels 18, 20, 24 and 26 disposed in inwardly folded relation over the medially folded bottom wall panel 12 and then opening the bottom wall panel 12 into place and disposing all of the liner panels 16 to 26 at the inner faces of the respective side wall panels 32 to 42.

During this setting up operation, the medially foldable liner panels 16 and 22 give sufficiently at the medial folds 28 and 30 therein to allow easy manipulation of the bottom wall panel 12 into place, and the double scores 44 and 46 at which the medially foldable liner panels 16 and 22 are foldably hinged on the side wall panels 34 and 40 result in providing a pronounced abutment disposition for the side edges of the medially foldable liner panels 16 and 22 at which the remaining liner panels 18, 20, 24 and 26 may be wedged effectively for supporting the bottom wall panel 12.

When desired, a corresponding form of separate liner structure 10' may be readily provided for nesting within the basket structure 10, as illustrated in Figs. 1 and 2, in which the corresponding elements of the liner structure 10' that may be seen are indicated by corresponding primed reference numerals. Also, the basket structure 10

of the present invention, whether or not provided with a separate corresponding liner structure '10', may be provided with any suitable form of lid structure (not shown) when desired.

The present invention has been described in detail above for purposes of illustration only and is not intended to be limited by this description or otherwise except as defined in the appended claims.

I claim:

1. A paperboard basket structure of the character described comprising an hexagonal bottom wall panel medially foldable across corners thereof, a liner panel foldably hinged at each side edge of said hexagonal bottom wall panel, the pair of liner panels at the opposed side edges of said bottom wall panel parallel with the medial folding axis thereof also being medially foldable at a parallel axis and having coextensive side wall panels foldably hinged at the opposite edges thereof, and additional side wall panels foldably hinged at the opposite side edges of each of said first mentioned side wall panels and respectively connected foldably and thereby forming an endless series including all of said side wall panels, whereby said basket structure may be disposed in collapsed form with said bottom wall panel medially folded and the respective liner and side wall panels at opposite sides of the medial fold therein arranged in face-to-face relation, and whereby said basket structure may be set up from said collapsed form to an erect form by opening said endless side wall panel series and inserting said medially folded bottom wall panel therein with all of the liner panels except said medially foldable pair disposed in inwardly folded relation over said medially folded bottom wall panel and then opening said bottom wall panel into place and disposing said liner panels at the inner faces of the respective side wall panels.

2. A paperboard blank for forming a basket structure of the character described, said blank comprising a medially foldable bottom wall panel, a pair of liner panels foldably hinged at opposite side edges of said bottom wall panel parallel to the medial folding axis thereof and also medially foldable at a parallel axis, at least four additional liner panels foldably hinged at the remaining perimeter of said bottom wall panel in symmetrical relation with respect to the medial folding axis thereof, a pair of side wall panels foldably hinged respectively on said pair of liner panels at the edges thereof opposite said bottom wall panel, and at least two additional side wall panels foldably hinged in series with each side wall panel of said pair at opposite edges thereof.

3. A paperboard blank as defined in claim 2 and further characterized in that one of said additional side wall panels on each of said pair of side wall panels and in complementary relation thereto have securing flaps formed thereon for foldably connecting all of said side wall panels in an endless series.

4. A paperboard basket structure of the character described comprising six side wall panels foldably connected in a continuous hexagonal series with an opposed pair

of said side wall panels having coextensive liner panels foldably hinged at the top edges and disposed at the inner faces thereof, each of said liner panels having a medial fold line parallel to its top edge, a hexagonal bottom wall panel foldably hinged between the lower edges of said liner panels and being medially foldable across corners along an axis parallel with said lower edges of said liner panels with the liner panels and bottom panel arranged so that upon folding of the bottom panel along said medial fold line the liner panels and bottom panel may be repositioned out of the enclosure of the side wall panels without disconnecting the continuous series of side wall panels, and four additional liner panels foldably hinged at their lower edges on said bottom wall panel and disposed coextensively at the respective inner faces of the remaining side wall panels of said series, whereby said basket structure may be disposed in collapsed form with said bottom wall panel medially folded and the respective liner and side wall panels at opposite sides of the medial fold therein arranged in face-to-face relation, and whereby said basket structure may be set up from said collapsed form to an erect form by opening said continuous side wall panel series and inserting said medially folded bottom wall panel and liner panels therein and then opening said bottom wall panel into place and disposing said liner panels at the inner faces of the respective side wall panels.

5. A paperboard blank for forming a basket structure of the character described, said blank comprising a hexagonal bottom wall panel medially foldable across the corners thereof, a pair of opposed liner panels foldably hinged at the opposed side edges of said bottom wall panel parallel with the medial folding axis thereof, a pair of opposed side wall panels foldably hinged to said pair of liner panels at the respective edges thereof opposite said bottom wall panel, and four additional side wall panels foldably hinged to at least one side edge of at least one of said pair of side wall panels, said pair of side wall panels and said four additional side wall panels being foldable to form a continuous series of six panels with the medial fold line of the bottom panel permitting folding of the bottom panel and liner panels into and out of the enclosure of said continuous series without disconnecting the series, each of said pair of liner panels at the opposed side edges of said bottom wall panel parallel with the medial folding axis thereof being also medially folded at an axis parallel to said bottom wall medial folding axis.
